COMBINED AUTOGRAPHED HANDBAG, WALLET, AND LOOSE LEAF RING BINDER

Marilyn Blaivas, Lawrence, N. Y.

Application February 5, 1958, Serial No. 49,514

Term of patent 3½ years

(Cl. D87—3)

Figure 1 is a front perspective view of a combined autographed handbag, wallet and loose leaf ring binder showing my new design in closed position; and

I claim:

The ornamental design for a combined autographed handbag, wallet, and loose leaf ring binder, substantially as shown and described.
